MIXER

Ferdinand H. Heine, Milwaukee, Wis., assignor to
 Koehring Company, Milwaukee, Wis., a corpora-
 tion

Application August 31, 1944, Serial No. 552,101

1 Claim. (Cl. 259—173)

1

The primary object of my invention has been to design a novel construction of mixer particularly adapted for the mixing of concrete aggregates, but also especially useful, because of the increased efficiency of the mixing action produced by the machine, for mixing of materials in glass, chemical, fertilizer, and other plants where dust conditions may prevail.

A broad phase of the novelty of my invention lies in the employment of a mixer comprising a mixing drum which is operated in such a manner as to move the mass of aggregates or materials therein in a plurality of planes whereby to accelerate the mixing operation to reduce the period of time required as compared with mixers in which the mixing drum is moved in one direction only for the agitation of the contents of the drum.

In the carrying out of my invention I have adapted my improved mixing functions to the type of mixer of the known tilting class wherein the drum is subjected to rotation during the mixing operation and is capable of being tilted to assume a position for charging, and reversely or downwardly tilted to assume its discharging position.

My invention is especially adapted for use with the last mentioned type of mixer in that I avail of the customary rotation of the tilting drum about its longitudinal axis for moving the mass of materials therein in one direction, and I operate the said drum while so rotating by a continuous back and forth tilting movement in a plane of oscillation or partial rotation at substantially right angles to the first mentioned rotation. In this manner I obtain the desired combination of movement of the mass of materials bodily, in different directions while the materials are being agitated by the blading in the mixing drum in directions that are yet different from the relative bodily movements above referred to.

A mixer constructed in the above manner produces, therefore, a new method of agitation or combination movements of the aggregates or materials in the mixer, speaking in reference to bodily movements of these materials as a mass, more particularly, and, so far as I am aware, this method of mixing has not heretofore been utilized in this art. The result of the combination mixing actions referred to is to speed up the completion of the mixing operation, a desideratum obviously important.

A further improvement in my invention, related to the foregoing, lies in the provision by

me of a closing door for the charging and discharging end of the tilting mixing drum, which door is maintained closed during the mixing operation and only opened for charging and discharging. Since the mixing drum, therefore, is closed while the mixing or agitation of the contents thereof is being performed, it is possible to operate the drum at larger capacity than in respect to previous mixers of the general tilting type, especially since the partial rotative tilting operation during mixing cannot under the conditions of use of a closed mixing compartment, throw the materials from the drum as it would do if the drum were not entirely closed. Because of the foregoing mode of operation utilizing the closed door principle, it will be possible to reduce the size of the mixing drum for a given volume of concrete to the extent that approximately four cubic yards of material may be mixed in a size of drum heretofore capable of handling approximately three cubic yards, with accelerated mixing operation additionally obtained.

With the above in mind, I note that I utilize special improved mechanism for controlling the opening and closing of the door with which the mixing drum utilized by me is equipped.

It has been proposed heretofore in the art of tilting mixers to utilize power means to tilt the mixer with partial rotary movement to its charging and discharging positions, as for instance is disclosed by my previous Patent No. 2,271,518; in the construction of the mixing device, however, the tilting action is not employed for purposes of mixing as indicated above.

One embodiment of my invention is illustrated in the accompanying drawings, and fully described in the following specification, and in said drawings:

Figure 1 is a general top plan view of a mixing machine embodying the improvements of this invention.

Figure 2 is an end view of the mixer.

Figure 3 is a side elevation, dotted lines showing the range of movement of the door to open position and general range of downward tilting movement of the mixer to its discharge position.

Figure 4 is a fragmentary sectional view taken about on the line 4—4 of Figure 1 and showing more particularly in section the drive gearing for effecting the rotation of the mixer about its longitudinal axis.

Figure 5 is a fragmentary sectional view bringing out more clearly the driving mechanism for causing the continuous back and forth tilting

movement of the mixer in a plane of its rotary movement.

Figure 6 is a fragmentary top plan view bringing out more clearly the operating mechanism for the door.

Figure 7 is a side view of the mechanism generally illustrated in Figure 6, also being a fragmentary view, dotted lines showing partially the position of the door actuating rods as when limited by the stop means controlling the limit of door opening movement.

Figure 8 is a fragmentary perspective view showing more clearly features of the door operating means of Figures 6 and 7.

Figure 9 is a fragmentary sectional and plan view of certain door operating parts seen in Figure 8.

Figure 10 is a detail view of a connecting pivot member of the door mechanism.

Figure 11 is a perspective view of the cradle member alone.

General construction of mixer

The general construction of my mixer is not unlike that used today and presented in my previously referred to patent, in relation to the mounting of the tilting mixing drum and certain operating mechanism therefor.

The mixer comprises the base 1 from which upwardly extend spaced pedestals 2 disposed at opposite sides of the mixing drum 3. The drum 3 is, generally speaking, of the usual oppositely tapered form and is supported for revolution about its longitudinal axis by means of a cradle or carriage 4, said cradle 4 being equipped with trunnions 5 projecting from opposite sides thereof and carried in bearings 6 at the upper ends of the pedestals 2. At its middle portion the cradle 4 is equipped with a suitable bearing 7 to receive a trunnion on the back or permanently closed end of the drum 3, the bearing 7 being equipped with suitable anti-friction bearings to take care of the thrust of the drum 3 with the contained materials therein as the drum rotates about its longitudinal axis.

The drum 3 is likewise equipped with the gear ring 8, see Figure 4, and roller track 9 welded or otherwise secured to the drum and surrounding its middle portion. Suitable rollers 10, see Figure 2, shown in dotted lines, are interposed between the curved body of the cradle 4 to support the central portion of the drum in connection with the cradle so that the drum may rotate freely with its ring gear 8 and roller track 9 upon the cradle 4. The foregoing generally describes the construction of my mixing drum and the cradle supporting means therefor substantially as heretofore known in the art, broadly speaking.

Drive for the rotation of drum

Figures 1, 2 and 4 illustrate the use of a motor 11 supported on a bracket 12 carried by one of the pedestals 2 of the machine, which motor causes the rotation of the drum 3 about its longitudinal axis. As seen clearly in Figure 4, the shaft 13 of the motor 11 carries a pinion 14 engaging a spur gear 15 in the housing member 16.

The gear 15 is provided with suitable bored holes 17 in which are located rubber covered bronze bushings 18 and said bushings receive pins 19 on the flange 20 of a hub 21 keyed or otherwise attached to the pinion shaft 22 which passes through the trunnion 5 of the cradle 4 adjacent to one of the pedestal bearings 6. The shaft 22

carried the bevel pinion 23 meshing with a bevel gear 24 keyed on the short drum driving shaft 25, said shaft 25 having keyed thereto a drive pinion 26 engaging the teeth of the ring gear 8 surrounding the drum 3.

In the operation of my machine the drum 3 is driven continuously, ordinarily, after starting the machine, by means of the motor 11; in other words, the rotation of the drum 3 about its longitudinal axis is continuous during the mixing operation as well as charging and discharging operations of the drum.

Tilting drive means for the drum

As previously indicated, it is proposed in my mixer construction to utilize a continuous back and forth tilting movement for the drum, or in other words, to impart to the drum and the mass of materials therein a continuous agitating movement incident to drum movement in a direction different from the movement which is imparted incident to the rotation of the drum about its longitudinal axis and by means of the blading therein. Figures 1, 2, 3, and 5 best show the tilting rotative operating mechanism now to be set forth.

In Figures 1 and 3 it will be noted that supported upon and adjacent to the base 1 of my machine is a motor 27 which may be an electric motor similar to the motor 11. Either of these motors may be self-contained power units, however, such as an explosive engine.

As seen in Figure 1, the shaft 28 of the motor 27 is connected by reducing gearing diagrammatically illustrated in Figure 5, affording driving connection between the motor and the driving pinion 29. The pinion 29 meshes with a combined gear and crank wheel 30 adjacent to one of the pedestals 2 and supported in keyed relation to a driving shaft 31 which carries at its opposite ends two of the crank wheels 30, one of which is engaged by the pinion 29. Connecting or pitman rods 32 connect the crank wheels 30 with suitable offstanding trunnion members 33 projecting from the opposite sides of the cradle 4, and the turning of the crank wheels 30 obviously imparts oscillating movement to the connecting rods 32, and the latter communicate such movement to the cradle 4 and thereby to the bodily carried drum 3 for effecting continuous oscillating or partial rotating movements back and forth to said drum 3.

For temporarily stopping the tilting movement of the drum 3 in the position of the Figure 3 illustration, at which time the closing door 34 of the drum may be opened to the dotted line position indicated in said figure, and for stopping the drum 3 at its tilted discharged position as indicated by lower dotted lines in Figure 3, there will be provided any suitable type of electric pneumatic or hydraulic brake such as designated 35 in Figure 1, the specific kind of brake not being material to the invention. In either of such stopped positions the door 34 may be opened as will be later described.

Consistency meter operating means

The employment of my drum 3 for bodily tilting continuous agitating, movement of the volume of aggregates or material therein advantageously makes for readily obtained indication of the range of variation of consistency of the materials that are being mixed in the drum 3. In other words, the resistance to the tilting driving torque for effecting the tilting action of the

drum 3 may be communicated to the bearing tube 36 in which the drive shaft 31 is supported upon the base of the machine by equipping the tube 36 with suitable spaced arms 37, see Figures 2, 3 and 5 particularly. Two pairs of these arms are provided and each pair is connected by a pivot pin connection 38 with a bracket 39 and one of the arms 37 extends downwardly at 37b to fit between travel limiting blocks 40. This permits a limited amount of travel of the last mentioned arm 37b, which amount of travel can be registered on suitable scale mechanism, not shown, of a consistency indicator, not shown, but to which the said arm 37b may be connected by a rod 41. A spring 42, see Figure 3, connects with said downwardly extending arm 37 to absorb shock and hold the rocker bearing tube 36 in a normal position. Obviously, deflection of the spring 42 may be used to measure the consistency of the materials which are being mixed in the drum 3. The rod 41 is directly connected with a rearward extension of arm 37b, which extension is designated 37a. By these means, including the pins 38, which are located slightly off the center line of direct thrust between the connections of the tilting arms 32 and main tilt frame, the application of the thrust of driving torque of shaft 31 to the torque tube 36, is enabled, for the purpose set forth. As the mixing continues the concrete materials pile up less and less in drum 3 and the variation in driving forces to effect mixing will be registered by any suitable indicator, or graphic recorder, operated by the rod 41.

Door and door operating mechanism

The closing door 34, previously mentioned, and operating means therefor are illustrated particularly in Figures 1, 3, 6 to 9 of the drawings. The end of the mixer closed by the door 34 is equipped with a suitable rubber or similar resilient gasket against which the door closes to provide a water-tight connection and from which the door is moved when opened. When so engaged with such gasket the door 34 rotates with the mixing drum 3. The door is directly carried in a rotatable manner by means of a cross-head or yoke 43 provided with a suitable bearing 44, see Figure 6, receiving a central trunnion 45 projecting from the door and affording the rotative mounting of the door on the cross member 43. The door 34 is operated to and from its closed positions by means of an air or hydraulic ram 46 carried by the cradle 4, see Figure 1, and the piston rod of which ram is connected by a member 47 with a bell crank lever 48. The bell crank lever 48 is connected by a cross rod 49 to a similar bell crank lever 50, the two levers 48 and 50 being pivoted to opposite sides of the cradle 4 at opposite sides of the mixer. The two bell cranks 48 and 50 are furthermore connected by rods 51 and 52, respectively, with the crosshead or yoke 43 by linkage and actuating parts now to be described in reference to Figure 3 and Figures 6 to 9, particularly.

The crossbar or yoke 43 is preferably curved so that if a battery of mixers of the type of my invention are arranged with their charging ends in a central charging zone closer setting of the mixers is permitted than would otherwise be the case.

The rods 51 and 52 are connected to door supporting and actuating rods 53 by linkage arm and lever parts which are the same for the both rods 51 and 52, and seen best in Figures 6 to 9, so that the mechanism for the rod 51 alone will be de-

scribed. The rod 51 or the rod 52, as the case may be, is attached at the pivot pin 54 to one end of a rocker lever 55 having hollow supporting bearing member 55a, the opposite end of which lever is connected by a pin 56 to a yoke 57; the yoke 57 in turn at the end opposite the pin 56 is connected to the trunnion or pin portions 58 of a block 59 which is attached to the rod 53 by the spaced clamping nuts 60. The action of the parts incident to a rightward movement of the rod 51 in Figure 7 is to rock the lever 55 to the dotted line position in said figure, thereby carrying the yoke 57 in a leftward direction and shifting the rod 53 longitudinally a very short distance sufficiently to cause said rod 53 to slightly open door 34 by moving it from the open end of drum 3. In this part of the door opening operation rods 53 of course act on the door 34 simultaneously. Each rod 53 moves over slides on a guide, rest, and stop member 61. The said door opening movement of each rod 53 is limited by the action of a nut E on its free end engaging an end of a rocker sleeve tilt and guide member C which is integral with bearing shaft or pin B, the parts that pass through the member 55a of lever 55, the parts 55a and 55b being supported in a sleeve bearing A on the cradle 4.

Thus the initial movements of rods 53 by pull on rods 51 and 52 slides rods 53 sufficiently to shift yoke 43 and slightly open the door 34 as stated. Then further pull on rods 51 and 52 rocks the levers 55 to the dotted line positions of Figure 7 after nuts E abut the tilting members C, thereupon the levers 55, yokes 57, rods 53, rock as units about the axes of the shafts or pins B, and the rods 53 are compelled to rise from their supported positions on the members 61. This will carry the cross head 43 and door 34, the latter now slightly spaced from the open end of drum 3, to a position fully at one side of said open end as per upper dotted lines of Figure 3.

The door 34 will usually be opened when the open end of drum 3 is at or nearly at its highest position and cleared of concrete materials being mixed, thus requiring little operating energy for actuation.

In closing, the operation of the rods 51 and 52 is that of pushing on connected ends of levers 55, lowering rods 53 first to points of resting on stops 61. The door 34 is thereby centered at the drum opening. Further reverse rocking of levers 55 slides rods 53 through tilt members C and nuts E move away from members C as parts 58 go below dead center positions and exert a pull on rods 53 pressing the door 34 into tight closing position at the drum opening.

Since the two rods 53 move together incident to the operation of the described unit at each side of the cradle, the door 34 will be carried upwardly by the two rods 53 because of their connection with the ends of the crosspiece or yoke member 43, and when so carried upwardly with the drum stopped from tilting in the position somewhat as shown in Figure 3 the drum 3 may be charged. In other words, the operation of the actuating units of Figures 6 and 7 as described is to impart movement in an upward direction relatively to the drum, to the door 34, and this relative movement may be performed when the drum 3 is to be charged in about the position shown in Figure 3.

General operation of machine

It is notable that by reason of the provision 75 of the rubber covered bronze bushings 18, see

Figure 4, the gear 15 is flexibly connected with the hub 17 and shaft 22, and this method of driving the shaft 22 and thereby the drum for its axial rotation absorbs the pulsating shocks out of the motor drive unit 11 and its associated gearing.

As seen in Figure 3, the mixing drum is illustrated as when it is turning about its longitudinal axis and at such time the drum will be continuously tilted up and down through an arc of about ninety degrees so as to create the two-directional mass shifting of the materials being mixed including movements of the materials from end to end of its drum. Of course, in the rotation of the drum around its longitudinal axis, the materials are likewise broken up, and agitating and pouring actions produced by the blading in the drum comprising one or more blades carried by the drum internally thereof and shown by dotted lines in Figure 1.

At such time as the mixing period is completed, under the control of any well known construction of batchmeter timing mechanism, the drum may be stopped in a position in which its discharge opening is downwardly opened by movement of the door 34 and the drum thus discharged. The batchmeter may operate, furthermore, to bring the drum 3 to its discharge position and effect opening of the door 34 automatically. After the mixing drum is stopped in its discharge position sufficiently long, the timing mechanism may control the movement of the drum to a charging position while the door 35 is opened for re-charging of the drum. As stated before, the brake 35 will be availed of for controlling the stopping and starting of the tilting action of the mixer as a part of the mixing function of the machine.

Effectively speaking, my machine and method hereof utilize means whereby to produce multi-directional continuous mass movements of the materials being mixed and during such movements the blading of the drum breaks up the mass of materials as such movements are imparted thereto. In this manner the mixing of the material is accelerated affording the time reduction factor previously referred to, and other advantages stated.

Having thus described my invention, what I claim as new and desire to secure by Letters Patent of the United States is:

In a concrete mixing machine, in combination, 5 a support, a concrete mixing receptacle adjacent to said support and formed with tapering ends, mounting means between said receptacle and said support comprising a cradle pivotally carried by the support and having a bearing therein, said concrete mixing receptacle being closed 10 at one end and equipped at such end with a bearing member operating in the bearing on said cradle, means for rotating the receptacle on the cradle about said bearing member as an axis, 15 and automatic means for rocking the cradle to continuously oscillate the receptacle in a direction endwise through an arc of approximately ninety degrees and at substantially right angles to its axis of rotation, said receptacle being provided with a charging and discharging opening 20 at its end opposite the bearing member end of the receptacle, together with means for maintaining closed the said opening during the continuous oscillation of the receptacle, whereby to prevent 25 material in the receptacle from being precipitated therefrom through said opening.

FERDINAND H. HEINE.
